UNITED STATES PATENT OFFICE.

JAMES WILLIAM PACKER, OF GLENS FALLS, NEW YORK, ASSIGNOR TO THE SANDY HILL IRON & BRASS WORKS, A CORPORATION OF NEW YORK.

TUBE-FORMING MACHINE.

1,258,441.

Specification of Letters Patent.

Patented Mar. 5, 1918.

Application filed August 9, 1916. Serial No. 113,844.

To all whom it may concern:

Be it known that I, JAMES WILLIAM PACKER, a citizen of the United States, residing in Glens Falls, county of Warren, 5 State of New York, have invented certain new and useful Improvements in Tube-Forming Machines; and I do hereby declare the following to be a full, clear, and exact description of the invention, such as will 10 enable others skilled in the art to which it appertains to make and use the same.

The present invention relates to the art of making tubes by winding a sheet of paper on a mandrel simultaneously with the application 15 of adhesive to one side of the paper, thereby building up a shell which subsequently can be stripped from the mandrel and will be strong and rigid because of the number of layers, and the binding and stiffening 20 action of the adhesive which holds those layers together. Such shells or tubes can then be cut to the proper length and notched at their ends, and can be used as cores for rolls of paper to be used in printing 25 presses of the continuous type, such as are now commonly employed in the production of newspapers.

It is an object of the present invention to provide a machine which is rugged in 30 construction and which is compact in design, this machine having means properly regulated for winding a paper sheet on a mandrel and for stripping the shell thus formed from the mandrel.

The mandrel of that embodiment of my invention which is illustrated in the accompanying drawings, is formed in two parts 35 detachably secured together, between which parts the forward edge of the sheet of paper may be clamped and held preparatory to the winding operation, one of these parts being tapered or wedge-shaped for removal from the other when the shell is to be stripped from the mandrel. Means is provided 40 for stripping the shell from the mandrel with power, use being made of a worm, operated through frictional driving means from the main power shaft of the machine. The stripping means operatively engages the 45 small end of the wedge-shaped part of the mandrel and pushes that off with the paper shell, and the entire operation of removing the shell from the mandrel is under easy control and offers no element of danger 50 either to the operator or to the machine.

To make possible the removal of the shell from that portion of the mandrel which remains in the machine, one of the mandrel bearings is of special design to open up and drop away, so that it offers no obstruction 60 in the path of the shell being stripped off. The other bearing of the mandrel remains undisturbed and may be of rigid and permanent character, holding the main part of the mandrel against swinging with respect to the machine frame. 65

The friction drive employed throughout the machine makes possible a wide range in the operating conditions and in the speed at which any step of the complete process 70 is performed.

In the accompanying drawings, illustrating an embodiment of the invention, and in which the same reference numerals refer to similar parts in the several figures, 75

Figure 1 is a view of the machine in side elevation;

Fig. 2 is an elevational view from the other side of the machine;

Fig. 3 is a front elevational view, parts 80 being broken away;

Fig. 4 is a sectional view taken on the line 4—4 of Fig. 3;

Fig. 5 is a detail view, in elevation, showing the mandrel bearing box in its disengaged position; 85

Fig. 6 is a detail sectional view taken along the line 6—6 of Fig. 3;

Fig. 7 is a detail sectional view of the split nut of the traveler; 90

Fig. 8 is a plan view of the body portion of the mandrel;

Fig. 9 is a plan view of the under side of the removable portion of the mandrel;

Fig. 10 is a side elevational view of the 95 body portion of the mandrel, with a portion thereof indicated in cross section;

Fig. 11 is a sectional view of the entire mandrel taken on the line 11—11 of Fig. 10;

Fig. 12 is a sectional view of the entire 100 mandrel taken on the line 12—12 of Fig. 10;

Fig. 13 is a view showing the manner of attaching the paper to the mandrel; and

Fig. 14 is an elevation of one end of the trough that holds the adhesive. 105

Referring to the drawings, 1 indicates a frame upon which a shaft 2 is rotatably supported and which carries a roll of paper 3 of which the tubes are to be formed. In order to control the speed of rotation of the 110

shaft 2 a tensioning device is provided comprising an arm 4 attached to the frame by a pivot-shaft 5 and adjustably connected to one end of a brake-band 6 which engages a brake-wheel 7 secured to the shaft 2, the other end of the band being fixed to the frame in any suitable manner, as by being connected to the pivot-shaft 5. A weight 8 is adjustably mounted on the free end of 10 the arm 4 and by varying its position the effect of the band upon the brake-wheel may be varied. A pin 9 projects from the arm 4 at any convenient point and enters a slot in a link 10 connected to an arm 11 which 15 may be adjustably clamped on a shaft 12 mounted in brackets extending rearwardly from the upper portions of the frame 1. When the shaft is rocked in a direction to raise the arm 11 the link 10 will ultimately 20 engage the pin 9 to lift arm 4 and render the brake-band inoperative thereby permitting free rotation of the shaft 2.

The paper in the course of its travel through the machine passes over a guide 25 roller 13 which may be adjusted by means under the control of a hand-wheel 14 at the front of the machine. From the roller 13 the paper passes over a roller 15 which is mounted upon a shaft 16 supported in depending brackets 17 from the under sides 30 of a pair of arms 18 clamped upon the shaft 12 in any convenient manner to swing therewith. Attached to the same shaft, but extending in the opposite direction is a second pair of arms 19 upon which weights 20 35 may be adjustably attached to counter-balance the arms 18 and the trough for holding paste or other adhesive attached thereto.

The paste trough of the apparatus comprises a base 21 having supporting brackets 22 attached thereto; the brackets being provided with slots 23 through which bolts 24 attached to the forward ends of the arms 18 pass. Nuts on the ends of the bolts permit 45 the supporting brackets to be clamped in any desired position of adjustment. As appears most clearly in Fig. 3, the arms 18 and the brackets 22 are preferably made of L-shaped cross-section and bolts 25 threaded 50 into the horizontal portions of the brackets bear upon the upper surfaces of the horizontal portions of the arms and are serviceable as jacks when adjustments of the trough on the arms are to be made.

55 The remaining parts of the paste trough comprise a front wall 26 provided with a drain aperture closed by a plug 27, a rear wall 28 and end walls 29. The bottom and front walls are preferably of wood. The 60 end walls are formed with bosses 30 which serve as bearings for a shaft 30' upon which is mounted within the paste trough a roller 31. On one end of the shaft outside of the trough is a pulley 32 which by means of a belt 33 is connected to a pulley 34 on shaft 65

16 which carries the roller 15. As the paper passes over the latter roller the rotation of the shaft 16 will, through the pulleys and belt described above, drive the roller 31 which should be partly submerged within 70 the paste in the trough.

At the upper rear corners the end walls 29 are cut away as shown most clearly in Fig. 14. A shaft 36 is mounted in brackets 37 which are adjustably mounted upon the 75 end walls 29 by means of bolts 38 and 39. Bolts 38 pass through vertical slots in the brackets 37 thereby permitting a vertical adjustment of the shaft 36, when bolts 39 are turned. The brackets are then clamped in 80 their adjusted, position by the bolts 38. Upon the shaft 36 is mounted a roller 40 for the purpose of transferring the paste from the roller 31 to the surface of the paper which in the course of its travel through the 85 machine passes from roller 15 upward along the rear surface of rear wall 28. Roller 40 is adjusted so that it engages roller 31 and at the same time engages the paper as the latter passes from the rear surface of the 90 rear wall. A cross-bar 41 extends between the end walls to which it is attached by means of screws 42. This bar is in front of roller 40 and serves as a guard.

As appears most clearly in Fig. 4 the 95 front face of the roller 15 is slightly to the rear of the plane of the rear wall 28. In order therefore to retain the paper against this wall as it passes upwardly from the roller 15 a guide 45 is provided. This guide 100 is pivoted to supporting brackets 45' so that it may be swung toward or from the rear wall 28 by means of a handle 46. The purpose of the above construction is to permit the guide to be used as a clamp for holding 105 the free end of the paper after a tube has been formed and severed therefrom and while the tube is being removed from the machine preparatory to again attaching the end of the paper strip to the mandrel upon 110 which the tubes are formed. If desired the guide 45 may be swung back out of the way to permit the paper to be carried through the machine when a new roll is added thereto.

115

Since the paste trough and its associated apparatus are all mounted upon the ends of the arms 18 they may be moved away from the mandrel and lowered into the position indicated in dotted lines in Fig. 4 by depressing the forward ends of these arms. In order, however, to limit the downward motion of the arms a pair of links 50 is provided. One of these links is attached to each of the arms 18 and each link is formed with a slot, 120 within which extends a shaft 51 mounted in bearings upon the top of the framework 1. This construction limits the possible downward movement of the arms 18. Means is also provided for limiting the upward move- 125 130

ment of these arms comprising a pair of cams 52 mounted upon the shaft 51 immediately above the arms 18. The upper surfaces of these arms engage the cams to limit 5 the possible upward movement of the arms. By rocking the shaft 51 to which the cams 52 are attached the position of the latter and consequently the limit of upward movement of the arms 18 may be adjusted. The shaft 10 51 may be retained in any desired position of adjustment by suitable clamping means.

When the paste trough is in the dotted line position indicated in Fig. 4 the machine is inoperative for forming the paper tubes 15 but at such times it may be desirable to provide means for rotating the paste rollers either for cleaning them or for preventing the paste from adhering to the surface of the rollers if they are not in motion. To 20 provide auxiliary driving means for this contingency a sprocket-wheel 55 is attached to the end of shaft 16 and when the paste trough is in its lower position the teeth of the sprocket-wheel engage a sprocket-chain 25 56 which passes over a wheel 57 mounted in brackets 58 at the bottom forward end of the framework 1. Toward the rear of the machine the sprocket-chain 56 passes over a second wheel 59 upon a shaft 60 mounted 30 in brackets 61 attached to the framework 1. Upon the same shaft is a pulley 62 which is connected by means of a belt 63 to a shaft 64 driven by a pulley 65 belted to the mechanism for driving the machine.

35 From the pasting roller the paper passes to the tube forming mandrel, which comprises a body portion 70, rotatably supported on the frame, and a removable wedge-shaped portion 71, between which portions 40 the end of the paper is gripped, as shown in Fig. 13, the section 71 being held in position by means of a removable ring 72 placed around the end of the mandrel, as shown in Fig. 10. The body portion 70 is provided 45 with a longitudinally extending groove 73 adapted to be engaged by a lug 74 projecting from the under surface of the removable portion 71 by means of which the inner end of the portion 71 is centered and held against 50 lateral movement relatively to the body portion, and in which groove the lug travels to act as a guide during the removal of the portion 71, as hereinafter described. The lug 74 is so positioned upon the portion 71 that, 55 when it engages the inner end of the groove 73 the inner end of the portion 71 will be spaced from the shoulder 75 on the body portion a distance sufficient to enable a key, hereinafter described, to be inserted therein, 60 whereby the key will engage the end of the removable portion. The inner surface of the removable portion is also provided with a recess 76, the outer end of which engages a projection 77 on the body portion, whereby 65 to center the outer end of the removable por-

tion with respect to the body portion and prevent lateral movement thereof.

The axle of the mandrel at the end thereof toward which the wedge portion 71 travels during its removal from the body portion is 70 journaled in a two-part bearing box, the construction of which appears most clearly in Fig. 5. This box comprises a lower part 80 carried by and preferably integral with a lever 81 pivoted to the frame and an upper 75 part 82 pivoted to the lever 81 whereby such part may be thrown into or out of operative relation to the lower part. Under normal or operating conditions the parts of the box are closed to receive the axle of the mandrel, the upper part being locked in position by a latch 83 and the box being held in elevated position by a rotatable support 84 which engages the lever 81 and which is provided with a shoulder 85 to engage the 80 frame to hold it in operative position. In order to disengage the box from the axle the latch 83 is moved out of engagement with the upper part 82 which is then rotated upon its pivot, after which the support 84 is removed out of engagement with the lever 81 90 allowing the latter to drop and carry the lower part 80 of the box away from the axle as shown in Fig. 5, the mandrel retaining its horizontal position because the shaft thereof 95 passes through bearings 86 and 87 at the top of the machine.

On the shaft of the mandrel between bearings 86 and 87 is secured a pulley 88 and a hand-wheel 89, the latter being for convenience in manual manipulation of the mandrel when attaching a new sheet of paper thereto. Pulley 88 is connected by a belt 90 to a pulley 91 secured to the main shaft 64. The belt 90 is normally slack and this slack 100 is taken up in order to render the belt operative when it is desired to rotate the mandrel by means of a tension roller 93 operatively connected to a lever 94, by which the roller may be moved into or out of engagement 105 with the belt.

The means for removing the wedge portion 71 of the mandrel after the tube has been formed comprises a traveler 100 supported upon a guiding rod 101 attached to 110 the framework 1. The upper end of the traveler 100 surrounds the mandrel and is provided with a slot 102 to receive a key 103 (Fig. 3), which is preferably attached to the traveler by a chain 104 and which, when 115 positioned in the slot, will engage the inner end of the wedge portion 71. The traveler 100 is also provided with a split nut consisting of a fixed upper section 105 having a smooth inner surface and a movable section 106 which is secured to a lever 107 pivoted to the traveler 100. The movable section is threaded as shown in Fig. 7 and by means of the lever 107 it may be moved into 120 or out of engagement with the rotatable 125 section 106.

worm 108 which extends through the split nut. A latch 109 is provided to hold the lever in its raised position in which the thread on the movable section of the nut 5 will engage the worm, thus causing the traveler to move from the right to the left, as seen in Fig. 3, when the worm rotates. As the key 103 when inserted in the slot 102 engages the inner end of the wedge portion 10 71 of the mandrel such portion will be forced to move to the left carrying the paper tube therewith, it being of course understood that the bearing box 80, 82 will be first disengaged from the mandrel axle as above 15 described, and that the ring 72 will be removed. The right-hand end of the worm terminates in a shaft which extends through a bearing 110 and has upon its end a gear 111 adapted to be engaged by gear 112 20 mounted upon a shaft 113 in brackets 114 attached to the top of the frame 1. Also upon the shaft 113 is a pulley 115 which is connected by a slack belt 116 with a pulley 117 upon the main shaft 64, the belt being rendered operative by means of a tensioning roller 118 mounted between the ends of a double arm bracket 119 which is pivoted at 120 to a fixed bracket 121 attached to the framework of the machine. Also 25 attached to the shaft 120 is a lever 122 having a counterbalancing weight 123 on its rear end. At its other end the lever is turned upwardly and then forwardly forming a handle 124 in a position convenient to 30 the operator of the machine. The counterweight 123 should be of such magnitude and so spaced from the shaft 120 that it normally retains roller 118 out of contact with the belt 116. When it is desired to rotate 35 the worm 108 to remove a finished tube from the mandrel, depression of the lever handle 124 causes roller 118 to engage the belt 116 and the latter then becomes operative to 40 drive the worm.

45 The operation of the parts described above is briefly as follows:

The paper is threaded through the machine over roller 13, under roller 15, between 50 guide 45 and rear plate 28, and the end thereof is then laid upon the body portion 70 of the mandrel, the wedge portion 71 at this time being detached from the remainder of the mandrel. While the paper is held in 55 place upon the body portion of the mandrel the wedge portion 71 thereof is replaced in position. The end of the paper is then gripped between these two portions of the mandrel as shown in Fig. 13. Thereafter the ring 72 is placed upon the end of the 60 mandrel and the bearing box 82 is returned to its normal position in engagement with the mandrel axle, it being of course necessary that this bearing box be out of place in 65 order to permit the replacement of the section of the mandrel. The paper being in

place, the lever 94 is moved to cause the tension of the roller 93 to take up the slack belt 90 whereupon the mandrel will be rotated to draw the paper through the machine and cause it to wind upon the mandrel to form a tube, the convolutions of which will be firmly secured to one another by the paste which is applied to the paper as it passes over the pasting roller 40, the latter being supplied with paste by the roller 70 71 which in turn is driven through the belt 73 from the guide roller 15 by the motion of the paper over the latter. When the tube is of the desired thickness the lever 94 is moved to its inoperative position and the 75 paper is severed from the formed tube in any suitable manner. The bearing box 80, 82 is then disengaged from the mandrel axle as above described and the ring 72 removed. The lever 107 is then raised and latched by 80 109 to hold the movable threaded section 106 of the split nut in engagement with the worm 108. The key 103 is placed within the slot 102 of sleeve 100 in position to engage the inner end of the removable portion 71 90 of the mandrel. The lever 122 is then moved to cause the tension roller 118 to take up the slack of the belt 116 whereupon the worm 108 will be rotated to move the traveler 100 from right to left as viewed in 95 Fig. 3.

During the movement of the traveler the wedge portion 71 will be forced off of the body portion 70 carrying with it the paper tube which will be retained in position thereon by frictional engagement whereby the traveler will not come into contact with the tube. When the traveler reaches the end of its path the roller 118 is moved into its inoperative position, the removable portion 105 of the mandrel is lifted off, and the tube removed therefrom. The latch 109 on the traveler is then disengaged from the lever 107 allowing the latter to drop thereby carrying the threaded section 106 of the split 110 nut out of engagement with the worm 108 and thereafter the traveler may be slid back to occupy its initial position.

After the tube has thus been formed it is necessary to cut the same to the desired 115 length and to form notches in the ends thereof, these notches being adapted to engage lugs on the point of the machine in connection with which the paper carried upon the tube is to be used. For the purpose of performing these two operations any desired 120 mechanism may be used.

Various modifications or changes in the details of construction of my invention may be made without departing from the principle thereof.

I claim:

1. In a machine for making paper tubes having a frame and a rotatable mandrel, a removable two-part bearing to support one 130

end of said mandrel, a lever pivotally mounted upon the frame and carrying one of said parts, the other of said parts being pivotally secured to said lever and releasable means to hold said bearing in its mandrel-supporting position.

2. In a machine for making paper tubes, in combination, a frame, a two-part mandrel rotatably supported thereon and held against movement perpendicular to its axis, one of the parts of said mandrel being removable, a worm parallel to said mandrel, means to rotate said worm, and means actuated by said worm to remove one of the parts of said mandrel together with the formed tube, said means comprising a threaded member movable into and out of engagement with said worm and means to lock said member in its worm-engaging position.

10 3. In a machine for making paper tubes, in combination, a frame, a two-part mandrel rotatably supported thereon and held against movement perpendicular to its axis, one of the parts of said mandrel being removable, a worm parallel to said mandrel, means to rotate said worm, and means actuated by said worm to remove one of the parts of said mandrel together with the formed tube, said means comprising a split nut sur-

15 30 rounding said worm and having a threaded section movable into and out of engagement therewith.

4. In a machine for making paper tubes, in combination, a frame, a mandrel rotatably supported thereby and comprising a body portion and a removable portion, a worm parallel to said mandrel, means to rotate said worm, and means actuated by said worm and engaging said removable portion to move the same relatively to said body portion.

5. In a machine for making paper tubes, in combination, a frame, a mandrel rotatably supported thereby and comprising a body portion and a removable portion a worm parallel to said mandrel, means to rotate said worm, a sleeve surrounding said mandrel and carrying a member engaging said removable portion, and a threaded member operatively connected to said sleeve and adapted to be moved into and out of engagement with said worm.

6. In a machine for making paper tubes, a mandrel comprising a permanently supported body portion and a removable portion, said portions having co-acting paper gripping surfaces, and detachable means to hold said removable portion in position upon said body portion.

60 7. In a machine for making paper tubes, a mandrel comprising a permanently supported body portion and a removable portion, said portions having co-acting paper gripping surfaces, one of said portions being provided with a recess and the other of said

portions being provided with means engaging said recess to prevent lateral movement of said removable portion.

8. In a machine for making paper tubes, a mandrel comprising a permanently supported body portion and a removable portion having co-acting paper gripping surfaces, said body portion being provided with a recess and said removable portion being provided with a pin adapted to engage 70 said recess to prevent lateral movement of said removable portion.

9. In a machine for making paper tubes, in combination, a frame, a mandrel rotatably supported by said frame upon which the 80 paper is wound to form a tube, a main driving shaft supported on said frame, means to rotate said mandrel from said main shaft, a pasting roller beneath the mandrel adapted to be engaged by the paper before it is 85 wound upon the mandrel whereby a coating of paste is applied to the paper, a mounting for said roller permitting the roller to be rocked upon said frame toward or away from the mandrel, and means associated 90 with said roller mounting for guiding the paper over the roller.

10. In a machine for making paper tubes, in combination, a frame, a receptacle for holding adhesive pivotally mounted on said 95 frame, a roller associated with said receptacle, a rotatable mandrel, means movable with said receptacle for guiding the paper over said roller, and means to rotate said mandrel to draw the paper over said guiding 100 means and said roller and wind it upon the mandrel to form a tube.

11. In a machine for making paper tubes, in combination, a frame, means rotatably supported thereon to hold a roll of paper, 105 a rotatable mandrel upon which paper is wound to form a tube, means to rotate said mandrel, arms pivotally mounted on said frame, a paste trough supported upon said arms beneath the mandrel whereby it may 110 be raised toward or lowered away from said mandrel, a pasting roller associated with said paste trough, and means mounted on said arms for guiding the paper over said paste roller.

115 12. In a machine for making paper tubes, in combination, a frame, means rotatably supported thereon to hold a roll of paper, a rotatable mandrel upon which paper is wound to form a tube, means to rotate said 120 mandrel, arms pivotally mounted on said frame, a paste trough supported on said arms whereby it may be moved to or from said mandrel, a pasting roller associated with said paste trough, means to counter-balance the arms and associated parts, and a guiding and clamping device mounted on the arms and through which the paper passes before passing over the pasting roller.

13. In a machine for making paper tubes, 130

- in combination, a frame, a shaft rotatably supported thereon to hold a roll of paper, a mandrel rotatably supported on the frame, arms pivotally mounted on said frame, a paste trough mounted on said arms whereby it may be moved to or from said mandrel, a guiding roller for the paper mounted on said arms, a paste-feeding roller mounted in said trough, means for driving said feeding roller from said guiding roller, a second roller adapted to be supplied with paste by said paste-feeding roller and to apply paste to the paper, means to guide the paper over said second roller, and means to rotate said mandrel to wind paper thereon and to draw the paper over said guiding roller and to rotate the same.
14. In a machine for making tubes, in combination, a frame, means associated therewith to hold a roll of paper, a mandrel upon which the paper is wound to form a tube, a main driving shaft, means to drive said mandrel from said shaft, a paste roller, means actuated by the travel of the paper for driving said roller, and means whereby said roller may be driven from said shaft when paper is not being wound upon said mandrel.
15. In a machine for making paper tubes, in combination, a frame, a shaft rotatably supported thereon to hold a roll of paper, tensioning means for controlling the rotation of said shaft, a second shaft mounted upon said frame, arms mounted upon said second shaft, a pasting roller supported upon said arms and a connection between said second shaft and said tensioning means whereby the latter is released when the said arms are depressed to carry the paste roller into inoperative position.
16. In a machine for making paper tubes, in combination, a frame, a mandrel rotatably supported on the frame, a main driving
- shaft, means to drive said mandrel from said shaft, a pasting roller, means for rotating said pasting roller, means actuated by the travel of paper for driving said pasting roller rotating means, and means for driving said pasting roller rotating means from said main shaft independently of the travel of paper.
17. In a machine for making paper tubes, in combination, a frame, a mandrel rotatably supported on said frame, a main driving shaft, means to drive said mandrel from said shaft, a paste trough, a pasting roller mounted in said trough, means for rotating said pasting roller, means actuated by travel of the paper as it is wound upon said mandrel for driving said rotating means, auxiliary means actuated from said main shaft for driving said rotating means independently of the travel of paper, and a movable support for said paste trough and pasting roller whereby said rotating means may be brought into position to be driven by said auxiliary means.
18. In a machine for making paper tubes, in combination, a frame, a mandrel rotatably mounted on said frame, a main driving shaft, means to drive said mandrel from said shaft, a pasting trough, a pasting roller mounted in said trough, a belt for driving said pasting roller, a roller actuated by the travel of paper as it is wound upon said mandrel for driving said belt, a sprocket chain driven from said main shaft, a sprocket wheel associated with said driving roller, a movable support for said trough and pasting roller adapted to permit said sprocket wheel to be brought into engagement with said sprocket chain whereby said belt and pasting roller may be driven independently of the travel of paper.

In testimony whereof I affix my signature. 25
JAMES WILLIAM PACKER.
